UNITED STATES PATENT OFFICE.

JOHN W. OFTELIE, OF BEARDEN, ARKANSAS.

DESIGN FOR A SIGN-PLATE.

SPECIFICATION forming part of Design No. 20,572, dated March 10, 1891.

Application filed February 4, 1891. Serial No. 380,239. Term of patent 7 years.

To all whom it may concern:

Be it known that I, JOHN W. OFTELIE, a citizen of the United States, residing at Bearden, in the county of Ouachita and State 5 of Arkansas, have invented and produced a new and original Design for Sign-Plates, of which the following is a specification.

By "sign-plates" I refer to plates for receiving letters for producing signs.

10 The leading feature of my design consists in an ornamental border surrounding a field or background ornamented by basket-work.

15 A is the background, and B the raised border. On the surface of the background appear longitudinally-ranging small figures *a*, between each of which appear corresponding small figures *a'*, that range transversely, the whole having the appearance of basket-work.

20 The surface of the raised border B comprises two series of small figures *c*, the said figures ranging longitudinally, presenting a chain-like appearance. At the corners of the border and at the center of the sides and ends the said chain-like series of figures *c*

are broken by interposed figures *D*, composed 25 of the concentric rings *d* *d'* and foliate figures *d''*, radiating from the outer ring *d'*, the inner ring inclosing an open-work figure *d''*. A series of parallel longitudinal lines *e* appear 30 between the two chain-like series of figures *c*, the said parallel longitudinal lines joining the several figures *D*.

At the inner edge of the border B, inside 35 of the inner chain-like series of figures *c*, appear the unbroken parallel lines *f*, that extend around the said border. At the outer edge of the border, outside of the outer chain-like series of figures *c*, appear the unbroken parallel longitudinal lines *g*, extending around the border. 40

I claim—

The design for a sign-plate herein shown and described.

JOHN W. OFTELIE.
